INFLATABLE SALVAGE DEVICE

Stewart S. Hathaway, 95 Milton Road, Rye, N.Y.

Filed July 1, 1957, Ser. No. 669,052

2 Claims. (Cl. 114—54)

This invention relates to a buoyancy device and in particular to an inflatable container suitable for use in changing the buoyancy of a body submerged in water.

Submerged vessels frequently carry enough valuable matter to justify extreme salvage efforts but, in any case, with the passage of time if the objective in investigating the vessel is not salvage it is likely to be pure curiosity. A variety of devices have been made for the purpose, each of which has its particular advantage in its own circumstances. In general, devices depend upon pontoons for raising the sunken vessel.

It is a fundamental object of this invention to provide a simple device inflatable after a time delay for use in altering the buoyancy of a submerged object.

It is another object of the invention to provide a simple inflatable device which can be placed in a submerged object and after a time automatically become inflated to displace a certain portion of water and alter the buoyancy of the submerged object.

It is another object of the invention to provide a device which takes advantage of the water as part of the mechanism of timing and also can use the water as an agent in the generation of gas for supplying buoyancy.

Other objects and advantages of the invention will in part be obvious and in part appear hereinafter.

The invention, accordingly, is embodied in a device which may be considered a valve or cartridge in combination with gas generating means and a gas retaining means, such that upon submersion in water, with action of the water, there is a time delay followed by gas generation and inflation of a cooperating gas container so that the ultimate inflated volume of the device is many times the volume of the uninflated device.

The invention, accordingly, is embodied in the agent containing cartridge and valve mechanism having the features of construction, the combination of elements and the arrangement of parts hereinafter to be described in greater detail.

In the drawings—

Figure 1 is a longitudinal section through the cartridge structure made in accordance with the invention;

Figure 2 is a longitudinal section through the device showing the parts after reaction and inflation of the gas container;

Figure 3 is a general diagram showing how the device is put to use, and

Figure 4 is a longitudinal section showing an alternative form.

Referring now to the drawings, in Figure 1, 10 represents the cartridge having a cylindrical body 11, with the ends having threads 12 and 13. The cap 14 is screwed over one end and the opposite is equipped with a collar 15 and the cap 16. The cap 16 is provided with at least one opening 17 equipped with a plug 18 which is reactable with water. An additional orifice 17' and plug 18' are shown. The plug 18 is made of a carefully predetermined size and composition so that the time of its reaction with water may be known with a reasonable degree of preci-

2

sion and to prevent the admission of water within the cap until the desired time interval has elapsed.

Internally, longitudinal shaft 20 extends substantially the length of the capsule and is provided at one end with 5 a plunger 21 fixed to the shaft by nuts 21'. Shaft 20 acts as a guide for the plungers within the capsule. At a point removed from plunger 21 by a known distance, plunger 22 is slidably mounted on the shaft. In the position shown in the drawing, a third plunger or collar 23 10 is fixed in the capsule approximately midway between the plungers or collars 21 and 22. Collar 23 is held in place by detents 24 and 25. The latter may take the form of set screws or any other equivalent mechanical devices. Orifices 27 and 28 in collar 23 provide for internal communication between the chambers 29 and 30 formed by the collars within the capsule. Any number of orifices corresponding to 27 and 28 may be provided. In general two or four will be adequate. Membrane or disk 23' is placed adjacent to collar 23 to effect separation of compartments 29 and 30 and prevents mixing of contents. It may be formed of plastic, not affected by acid used, and sufficiently thin to be broken under pressure. Also, orifices 31 and 32 in the wall of the capsule are provided to communicate with the exterior of the valve. Tapered plugs 31' and 32' are set in these orifices to prevent entry of water, yet to permit blowing them out by internally generated gas. Surrounding the entire structure is the 15 inflatable bag or container 35 which is tightly fastened around the neck of the capsule by means of the collar 15. Plug 18, which is the seal, may be made of any metal which is quickly corroded by water. It also must be of a size adequate to withstand the pressure at which the device is to be used. Herein is one of the advantages of this structure over underwater devices which employ a 20 frangible disk. Any device using the frangible disk does not permit time delay beyond that required to place it at the predetermined depth.

For purposes of this invention, aluminum disk or plugs are desirable for a relatively long period of delay. For 25 shorter periods magnesium or magnesium-aluminum alloys may be used. These latter are of value, because they have high strength, but the magnesium is quite reactive with water and the plug may be made to dissolve with relatively high degree of time control.

Plunger 21, as shown, may consist of a metal disk with a matching rubber seal 21". Plunger 22 is similarly constructed with seal 22". Rubber or other synthetic rubber-like sealing material which will provide a close fit is useful.

The chamber 29 is charged with a chemical material 30 reactable with additional chemical material placed in the chamber 30 to produce a gas. In operation, therefore, when the device is submerged and the plug 18 is dissolved, hydrostatic pressure applied to the plunger 21 moves it toward the fixed collar 23, thereby applying 35 pressure to disk 23', fracturing it and forcing material from chamber 29 into chamber 30 where reaction takes place. The gas generated forces collar 22 to slide on shaft 20 to a position corresponding, for example, to that shown in dotted lines, where it is stopped by stop 40 nut 20', whereupon gas pressure builds up within the chamber, dislodges plugs 31' and 32' and gas escapes through orifices 31 and 32 to inflate the bag 35. Upon exhaustion of the chemical material by full reaction, the bag will be rather fully inflated and there is little 45 danger of having the gas escape. Relief valves 36 and 37 may be set in the bag 35 to keep gas pressure in the bag to a safe level. Also, the amount of gas to be generated is subject to close control by the size and nature 50 of charge used in chambers 29 and 30.

Suitable reactant materials for enclosure within the 55 chambers 29 and 30 are acid materials for 29, such as

sulfuric or acetic acids, and for the chamber 30 alkali metal carbonate or bicarbonate. It is preferable that the reactants used leave a water soluble or non-bulky residue. However, despite this matter, it is also possible to use calcium carbide in chamber 30 and water in chamber 29. The only disadvantage of this combination is that the acetylene produced is flammable and can involve some risks in the ultimate work around the vessel.

Since the device may be treated as expendable and may be intended for single occasion use, the materials of construction may correspond. Generally, I have found common iron pipe, fittings, and rod useful for the body 11, caps 14, 16, collar 15. Internal plungers 21, 22 and collar 23 may be of rubber or synthetic rubber materials, for example. Alternately a complete plastic device may be used. That is, all parts may be formed of materials such as polyethylene plastic, polytetrafluoroethylene (Teflon), or butyrate plastic. These synthetic materials possess the advantages that they can be assembled and joints made integral by heat sealing or the use of solvents and cements.

The inflatable bag 35 may be formed of any suitable gas retaining material, for example, a plastic sheet of appropriate gauge, such as polyvinyl chloride, polyethylene plastic or even a rubber bag will do. Its size is proportioned to the size of the capsule used so that the amount of gas generated within the capsule is approximately an optimum amount for inflating the bag to the desired degree. In providing the bag, the depths at which it is to be used must be taken into account and it should be provided with relief valves or be inflated with a volume of gas which it can retain at sea level. That is, if used at extreme depth and inflated at extreme depth, the gas would be under quite high pressure (30 feet of water would be an extra atmosphere of pressure) and, accordingly, the bag could burst as it reached the surface. This phenomenon also works to the advantage of the device for in raising a vessel by placing inflated bags in it, the decompression of the gas after an equilibrium floating buoyancy is reached, increases the net buoyancy of the vessel and causes it to rise rapidly.

Figure 3 illustrates the means for using the capsules in a salvage operation. In Figure 3, 50 represents a body of water in which a vessel 51 is submerged and rests on the bottom 52. A barge 53 having located the sunken vessel can connect with it by means of open pneumatic lines 54 and 55, these being applied by divers. A suitable number of devices made in accordance with this invention are inserted and delivered to the sunken vessel by way of the hoses. In fact pneumatic delivery tubes in which compressed air is the motive power are useful. Within the calculated period after delivery of the capsules to the vessel, reaction with the water in the submerged vessel will bring about chemical reaction within the capsule and inflation of the bags. The cumulative effect of a number of such bags, inflated, is sufficient to raise a vessel of any size. The time delay made possible by the water-reactive plug in the capsule is very useful

to divers, because a plurality of the capsules may be taken down to a vessel and carefully set in place, with ample time for the diver to do the job and leave the scene.

Figure 4 illustrates an alternative form of device in which the structure is varied. Therein shaft 20, and collar 23 correspond to those shown in Figure 1. Plunger 40 corresponds to 22 of Figure 1 but is fixed in place on shaft 20 by stop nuts 41 and 42. In operation, therefore, when plugs 18 and 18' dissolve, plungers 21 and 40 move with shaft 20, i.e., to fixed collar 43 which is held in place by detents 44 and 45. Shaft 20 slides freely in collars 23 and 43 and the amount of movement is fixed by the distance between the end of shaft 20 and the cap 14. Vents 31 and 32 are spaced from collar 43 sufficiently to permit free discharge of gas when the plunger 40 has moved past orifices 31 and 32.

Though the invention has been described with reference to only a limited number of examples, it is to be understood that variants thereof may be devised without departing from its spirit or scope.

What is claimed is:

1. A device for providing a time delayed action for inflation of a gas-retaining container in a position submerged in water, comprising a suitable bag for retaining a gas, a capsule enclosed within said bag, a cap at one end of said capsule providing exterior communication and comprising a closure therefor, said capsule having internal sub-divisions, said sub-divisions containing gas generating means, an orifice in one of said sub-divisions providing communication with the interior of said bag, and a water reactable plug in said cap, whereby following reaction of said plug with water hydrostatic pressure forces said gas generating means to generate gas and inflate said container through said orifice communicating with the interior of said bag.

2. A device for providing delayed action inflation of a gas bag in a water submerged position, comprising a bag having an opening therein and suitable for retaining a given volume of gas, a capsule enclosed within said bag, the opening in said bag being gathered around one end of said capsule, a cap covering said end of said capsule and forming a closure therefor, said capsule having a plurality of internal sub-divisions, said sub-divisions containing gas generating reactants, one of said sub-divisions having an orifice communicating with the interior of said bag, said cap being at least partially water reactable to dissolve therein, whereby following submersion of the device and reaction with water, hydrostatic pressure forces mingling of gas generating reactants within said capsule, thereby to generate gas and inflate said container.
